US0D1076952S

(12) **United States Design Patent** (10) **Patent No.:** **US D1,076,952 S**
Mulyono et al. (45) **Date of Patent:** **** May 27, 2025**

(54) **DISPLAY SCREEN OR PORTION THEREOF WITH GRAPHICAL USER INTERFACE**

(71) Applicant: **Salesforce, Inc.**, San Francisco, CA (US)

(72) Inventors: **Alwin Mulyono**, Montara, CA (US); **Pavithra Ramamurthy**, Dublin, CA (US)

(73) Assignee: **Salesforce, Inc.**, San Francisco, CA (US)

(**) Term: **15 Years**

(21) Appl. No.: **29/911,955**

(22) Filed: **Sep. 12, 2023**

(51) LOC (15) Cl. **14-04**

(52) U.S. Cl.

USPC **D14/486**

(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The dot-dash broken lines in the figures and the areas within the dot-dash broken lines show portions of the graphical user interface that form no part of the claimed design.
